United States Patent Office

Des. 210,596

Patented Mar. 26, 1968

210,596

ELECTRONIC POWER SUPPLY CASE OR SIMILAR ARTICLE

Brant W. Becker, Sudbury, Mass., assignor to Gordon Engineering Company, Waltham, Mass., a limited partnership of Massachusetts

Filed June 7, 1967, Ser. No. 7,390

Term of patent 14 years

(Cl. D26—15)

FIG. 1

FIG. 2

FIG. 1 is a perspective view of an electronic power supply case or similar article showing the new and ornamental features thereof; and

FIG. 2 is another perspective view of the case of FIG. 1 showing the other three sides thereof.

The dominant features reside in the full line portions. What is claimed is:

The ornamental design for an electronic power supply case or similar article, substantially as shown and described.
